LACE MECHANISM FOR STRAIGHT
KNITTING MACHINESMax Richter, West Reading, Pa., assignor to
Textile Machine Works, Wyomissing, Pa., a
corporation of Pennsylvania

Application October 13, 1933, Serial No. 693,454

3 Claims. (Cl. 66—96)

This invention relates to straight knitting machines and more particularly to mechanism applicable to standard full fashioned knitting machines for producing symmetrical decorative lace work or clock effects in allochiral figures in the knitted fabrics or hosiery, and to a novel method of operating the same.

Flat knitting machines have heretofore included more or less intricate mechanisms for the production of lace clock or other designs, but the mechanisms so employed have been subject to certain limitations and disadvantages in their operation and in the results produced. In practically all cases of machines equipped with standard lace devices or mechanisms it has not been possible to cause a plurality of separate lace fingers at each knitting section, mounted on lace rods movable independently of the narrowing rods, to move simultaneously toward or away from each other, but only unidirectionally. Furthermore, in cases where a design to be produced has included a plurality of repeated figures in a given section, as for instance at the opposite sides of a stocking blank, the resultant design has been unsymmetrical in that the repeated figures in a single knitting section have been duplicates and identical in arrangement, rather than allochiral. This has imposed a limitation upon the character of such designs to more or less regular and uniform geometrical shapes or patterns; that is to say, a design including an angular or curved portion would have the angular or curved portion extending in the same direction in the repeated figure or figures, and it has not been possible to produce lace clock openings in fancifully curved or arbitrarily arranged figures or designs which are complementary to each other, in the respect that one is a reversed replica of the other, so that the repeated figures produce a desired symmetrical effect.

Also, in view of the fact that the simultaneous movements of the lace fingers in prior constructions have been unidirectional, the area or needle distance in which the lace fingers have been able to operate has necessarily been subject to restriction, so that complete designs produced at the center of the knitted fabric blank, as for decoration of the instep portion of the finished stocking, have been limited to a thirty needle movement or less of the lace fingers.

An important object of the present invention is to enable a standard full fashioned knitting machine to produce symmetrically curved or otherwise shaped lace clock or other designs by simple and efficient means whereby the usual

lace or transfer points are rendered movable simultaneously toward or away from each other in each half of the knitting section as well as across the center of the knitted blank, and independently of the usual narrowing rods of the machine.

Another object of the invention is the provision of a lace attachment for standard full fashioned knitting machines, including a pair of simultaneously oppositely movable lace rods each of which carries lace fingers and lace points applicable to each of a plurality of sections of the knitting machine.

A further object is the provision of a motion reversing device of the foregoing character for use with full fashioned knitting machines equipped with standard lace attachments whereby the movement of the usual point shifting mechanism is communicated to a pair of lace rods in such manner that the latter are oppositely moved toward or away from each other, carrying the lace points therewith and making possible the production of complementary curved or other designs covering a distance of at least sixty needles, in contradistinction to the usual thirty needles, at the center of the leg blank for formation of instep or other decorations.

An additional object of the invention is the provision of a simplified lace clock attachment of the foregoing type for full fashioned knitting machines which may readily be supplied to existing installations, whereby the machines may be easily equipped to produce complementary knitted designs.

The invention further includes a novel method of producing complementary lace clock hosiery ornamentations on standard full fashioned knitting machines.

With these and other objects in view, which will become apparent from the following detailed description of the illustrative embodiment of the invention shown in the accompanying drawings, my invention resides in the novel methods, elements of construction, mechanisms and combination of parts in cooperative relationship, as hereinafter more particularly pointed out in the claims.

In the drawings:

Figure 1 is a diagrammatic representation of a portion of a full fashioned stocking blank illustrating a design effect obtainable in accordance with my invention;

Fig. 2 is a partial front elevational view of a full fashioned knitting machine embodying lace

mechanism in accordance with one form of my invention;

Fig. 3 is a plan view of automatic narrowing head control mechanism adapted for use in conjunction with certain mechanisms of my invention;

Fig. 4 is a transverse vertical sectional view, taken substantially on the line 4—4 of Fig. 2, looking in the direction of the arrows;

Fig. 5 is a view looking from above and generally in the direction of the arrow A in Fig. 4, showing details of the lace mechanism with certain parts thereof broken away;

Fig. 6 is a front view of the mechanism shown in Fig. 5 looking along the line 6—6, with certain parts of the mechanism broken away;

Fig. 7 is a vertical sectional view taken substantially on the line 7—7 of Fig. 6;

Figs. 8 and 9 are plan views of the design or pattern cam members employed in the lace mechanism;

Fig. 10 is a partial front elevational view of a full fashioned knitting machine showing a modified form of the invention applicable to machines supplied with conventional lace clock attachments.

Fig. 11 is a plan view of certain parts of the mechanism shown in Fig. 10, taken substantially on the line 11—11 of the latter figure;

Fig. 12 is a vertical sectional view taken substantially on the line 12—12 of Fig. 10;

Fig. 13 is a front view of another form of device for effecting opposed movement of the lace finger rods, with certain parts of the device broken away; and

Fig. 14 is a side view of the device shown in Fig. 13.

Only those parts of a straight knitting machine necessary for an understanding of the invention are shown in the drawings; the various other parts and mechanisms and their manner of operation being well known in the art, as shown and described in detail in the "Reading" Full Fashioned Knitting Machine catalogue, copyrighted 1929, and published by the Textile Machine Works, Reading, Pennsylvania.

Referring to Fig. 1 of the drawings, the numerals 20 and 21 designate opposite edges of the lower part of the leg portion of a full fashioned stocking blank, including the usual narrowing or fashion marks 22 and 23 at the edges 20 and 21 respectively. The stocking blank is provided with an ornamentation produced in accordance with the invention, here shown as lace clocking in two complementary portions 24 and 25 at the opposite edges of the blank. It will be seen that the ornamental figure 24 initiates in a regular geometrical pattern extending wale-wise of the blank and terminates in a portion 26 extending downwardly, inwardly and upwardly in a curved path toward the center of the blank.

With lace mechanism as heretofore used, having two lace points operating unidirectionally, the ornamental portion 25 would be an exact counterpart of the portion 24, with its lower portion 27 extending in the same direction as the portion 26, outwardly toward the edge 21 of the flat stocking blank so that when the stocking had been completed and seamed one of the lower ornamental portions would extend toward the instep and the other toward the heel of the stocking. In accordance with the present invention, however, the lace points operate in opposite directions, toward and away from each other, so that the several corresponding parts of the re-

spective ornamental portions are not only substantial counterparts of each other, but are also complementary, as shown in Fig. 1, resulting in a symmetrical and balanced design effect with the ornamental parts 26 and 27 extending toward each other at the instep in the finished stocking. Also, in the arrangement shown the openwork effect appears at the opposite contiguous or outer sides, as the case may be, of the plurality of figured parts of the design, thus functioning as an external or internal outline or border for the combination and presenting a balanced appearance. The form of the design shown in Fig. 1 is for illustrative purposes only; practically an unlimited range of the design effects is possible as will hereinafter appear.

Referring to Figs. 2 to 9 of the drawings, there is shown one form of lace mechanism in accordance with the invention applicable to a full fashioned knitting machine not previously equipped with a lace clock attachment. The machine in this instance is shown as comprising a frame of conventional construction including front and back beams 14 and 15, front and center beds 16 and 17, and frames 18 in which is mounted the main cam shaft 28 provided with the usual knitting cams for actuating the bank of needles 29 and coacting loop forming elements in the well known manner.

The narrowing mechanism N is of the usual construction and includes the narrowing points 19 carried on narrowing rods 44 slidably mounted in supports 43 secured to the front narrowing shaft 70 of the narrowing machine, the necessary vertical movements being imparted to the narrowing points by dipping the narrowing machine through lift levers 57 pivotally connected to the front narrowing shaft, the levers 57 being actuated by rollers 58 which are in engagement with narrowing lift cams 59 when the cam shaft is shogged to the narrowing position by the shifting mechanism S under control of the pattern chain motion mechanism C.

The lace mechanism includes various elements of the narrowing mechanism and at least two lace rods 39 and 40 each having at least one lace point, 31 and 32 respectively, operable in the same knitting section. There is also preferably, although not necessarily, provided a picot rod 42, the latter carrying the picot bars 30. Each of the foregoing rods is carried by the narrowing machine which imparts the necessary vertical movements thereto, the operation of the lace and picot mechanism being controlled by shifting the cam shaft to the narrowing position.

Since the lace clocking mechanism D and the narrowing brackets 43, maintaining the rods 44 and narrowing fingers 19, are both affixed to the front narrowing shaft 70, they are, in turn, unitedly moved up and down therewith during each revolution of the cam shaft 28 while in its shifted position; nevertheless, auxiliary means is provided to permit for independent operative actions of either the lace or narrowing rods as generally illustrated in Fig. 3. The chain motion mechanism C, Figs. 2 and 3, includes a pattern chain 66 having series of control buttons affixed thereon. The buttons of series 3 determine the courses in which a narrowing operation is to take place and control the regular narrowing shifting movement of the cam shaft through actuation of the shifting device S in the well known manner, and simultaneously actuate the narrowing head mechanism N in a manner hereinafter described; while the buttons 6 and 67 coopera-

tively function to determine which courses shall be lace pattern courses by causing shifting of the shaft 28, without actuating the narrowing head mechanism, in predetermined courses when effecting the lace clock design.

In order to operate the lace clocking unit D so as to impart the desired transverse movement to the point rods 39 and 40, without operating the narrowing heads indicated at N, the mechanism shown in Figs. 2 and 3 is employed. Thus coincident with the positioning of one of the buttons 67 beneath the lower extension of the pivoted lever 68, one of the buttons in the track 6 is operatively positioned beneath the lever 7. The clockwise movement of 68 imparts a similar movement to the support member 60 through means of the intermediate link 69 thereby breaking engagement between the recess 64 and the arm 54 and, in turn, permitting the cam follower 55 to follow the contour of its respective cam 56; said action being effected through means of the coil spring 65, Fig. 4, whereupon the unit D is operated thereby in the desired manner as hereinafter more fully described. Meanwhile, the raising of lever 7 by one of the buttons 6 lifts the lock lever 8 through means of the intermediate screw 9, affixed to said lever 7, which abuts the extension 8a of lock lever 8. Releasing the lock lever 8 from engagement with the recessed portion of plunger 10 permits the cam shaft shogging mechanism S to operate in the usual way, thereby axially shifting cam shaft 28 into the position necessary to operate the lace clocking mechanism D in the desired manner.

It will be observed in Fig. 2 that the narrowing head actuating cam 12 is sufficiently removed from its respective cam follower 13, so that shifting of the cam shaft 28 will not in itself bring said members 12 and 13 into cooperative engagement with each other; consequently, during the operation of the lace clock unit D, as previously explained, the narrowing head mechanism N will remain inoperative.

When the usual narrowing stitches are to be effected independent of the lace clocking mechanism one of the narrowing buttons 3 of the respective series, Fig. 3, is positioned beneath the horizontally extending arm (not shown) of lever 1 in turn copivately mounted with the lever 7 and lock lever 8 on the stud 5 and has a portion thereof (not shown) extending beneath the lock lever 8. Thus counter clockwise movement of lever 1 effected by button 3 imparts corresponding movement to the latch 11 while the lock lever 8 is raised out of engagement with the plunger 10 causing the cam shaft 28 to be shifted in manner heretofore explained without, however, placing the mechanism D into operation. The lever 1 is connected by a rod 1a with the latch 11 controlling the dropping of a roller 35a into operative engagement with a face cam 35 mounted on the cam shaft 28. The roller 35a is carried on a swinging extension 36a of a centrally pivoted lever 36 connected to the upper end of a centrally pivoted lever 37. The lower end of lever 37 is connected to a rod 11 which slidably controls, by means of a centrally pivoted lever 2, the position of the shiftable roller 13 relative to the cam 12. The roller 13 is carried by a lift lever 38 which controls the operation of the narrowing head mechanism in a manner well known in the art. Thus the operative positioning of one of the buttons in series 3 beneath the horizontally extending arm of lever 1 in addition to lifting the lock lever 8 and thereby placing the cam shaft shift-

ing mechanism into operation, will likewise, through means of the intermediate members heretofore detailed, shift roller 13 leftward, Fig. 2, into alignment with its respective cam 12 whereupon the narrowing mechanism N will operate independent of the lace clock unit D. The roller 4 coaxing with a cam surface on the periphery of cam 35 is used to lift lever 36a and permit latch 11 to engage and inoperatively maintain the lever 36b following the operation thereof. Simultaneous operative positioning of buttons from each of the series 3, 6 and 7 will cause the narrowing mechanism N and the lace clocking unit D to effect narrowing stitches and lacework in the same knitted course; consequently by positioning the control buttons in the desired sequence either independent or combined operation of the narrowing and lace units may readily be effected.

Referring particularly to Figs. 2 and 4 the lace points 31 and 32 of each knitting section are carried by lace fingers 33 and 34, these fingers being carried by a pair of lace point rods 39 and 40 respectively. In accordance with the invention the lace point rods 39 and 40 are mounted for reciprocable movement toward and away from each other in bearings 41 carried by front narrowing shaft 70.

Pivots attached to the arm 45, in surrounding relation with the pin 46, is one end of a forked actuating link 47. The opposite end of the link 47 is pivotally connected to a lever 48 which is pivotally mounted on the back narrowing shaft 49. Pivots attached to the lever 48 is one end of a link 50, the opposite end of which is pivotally connected to one arm 51 of a lever 52. The lever 52 is pivotally mounted at 53 to a fixed portion of the machine.

The second arm 54 of the lever 52 is provided with a cam follower 55 which is adapted to be engaged by a cam 56 secured to the main cam shaft 28, whereby each revolution of said cam shaft, while the latter is in its shogged position, through the system of levers, links, etc., just described, causes simultaneous rotation of the lace point rod actuating cams 71 and 73 hereinafter described in detail.

The lever 52 is normally held out of operative engagement with the cam 56 by means of an upwardly extending supporting rod 60, the lower end 61 of which is rockably mounted on a pin 62 extending forwardly from a bracket 63 fixed to a portion of the machine. The end of the arm 54 is arranged to be normally seated in a recess 64 formed in the upper end of the supporting rod 60. A tension spring 65 supported on the back narrowing shaft 49 and connected to the outer end of the lever arm portion 51, tends to normally maintain the lever 52 in position upon the support 60, and also to maintain the follower 55 in engagement with the cam 56 when the support 60 has been withdrawn from the lever arm portion 54.

Means are preferably provided to predeterminedly release the lever 52 from the support 60, thus to control the action of the cam 56 upon the lever 52 in the latter's movement effecting operation of the lace point rods 39 and 40. In this instance said means consist of a pattern chain 66 having a plurality of buttons 67 operable on a pivoted lever 68 which acts through a rod 69 to actuate the support rod 60 by moving the latter away from the lever arm 54, thus causing the follower 55 to traverse the cam 56.

As a means for operating the lace point rods 39 and 40, the form of the invention shown in Figs. 2 to 9 includes a novel lace clock attachment indicated generally at D. Rigidly secured to the front narrowing shaft 70 is a bracket 72 which is provided with a bearing 73 for rigidly supporting a transversely extending shaft 74 one end of which is screw threaded into said bearing.

Rotatably mounted on the shaft 74 is a ratchet wheel 75 provided with a hub 76 having a pair of eccentric cam discs 77 and 78 secured thereto by suitable screw fastenings 79; and between the cam 78 and ratchet wheel 75 there is freely mounted an actuator member 80, arranged for cooperation with the ratchet wheel, as hereinafter described. One end of the hub 76 is held in frictional engagement with a spacing member 81 provided at the bearing 73 by means of a resilient plate or brake element 82 which engages the outer face of the ratchet wheel 75 at the opposite end of the hub 76, whereby the ratchet wheel and cam discs are maintained in relative fixed position during reverse movements of a pawl 83 carried by the member 80, by which intermittent rotation of the ratchet wheel and cam discs in one direction is effected.

The pawl 83 is pivotally mounted at 84, on the actuator member 80. The actuator 80 is rocked in one direction by a coiled spring 86 having one end attached to the actuator and its opposite end secured to an anchorage 87 which is secured to the front narrowing rod 70.

Movement of the actuator 80 in an opposite direction to advance the lace rod cams 77 and 78 step by step in accordance with the spacing of the teeth of the ratchet wheel 75 is effected by a bell crank lever 88 which is pivotally mounted on the bracket 72 as seen at 89, with one arm 90 of said bell crank underlying and engaging an arm 91 formed on and extending from the actuator member 80, the second arm 92 of the bell crank lever lying in engagement with the pin 46 mounted in and extending laterally from the arm 45 mounted on the narrowing rod 70.

Means are provided to operatively connect the cam discs 77 and 78 and the lace point rods 39 and 40, respectively, whereby the latter are selectively shifted longitudinally in opposite directions, toward or away from each other, to adjust the lace points of each section, (for instance the points 31 and 32), different distances apart for production of various desired transferred loop effects in the knitting.

The cam discs 77 and 78 in this instance are of like eccentric form and of increasing diameter in opposite directions as seen in Figs. 8 and 9. Each has its smallest diameter portion 93 and its widest diameter portion 94 initiating and terminating, respectively, in the same radial plane. A plurality of elevations and depressions 95 and 96 respectively, are formed along the outer edge, with a dwell 97 between the portions 93 and 94 (91a in Fig. 9). These elevations and depressions constitute stepped cam surfaces arranged to determine the engaging position and extent of movement of the lace point rods.

Cooperating with the cam discs 77 and 78 are a pair of crossed actuating levers 98 and 99 pivotally mounted on a short shaft 100 extending from the bracket 72. The levers 98 and 99 are provided with cam follower portions including rollers 101 and 102 respectively, arranged to engage the edges of the cams 77 and 78, and depending forked toe portions 103 and 104, respectively arranged to

engage collars 105 and 106, respectively, provided on the lace point rods 39 and 40.

Means are provided to maintain the cam follower rollers 101 and 102 in continuous engagement with the cam discs and the toes 103 and 104 in engagement with the collars 105 and 106 whereby pivotal movements of the levers 98 and 99, effected by rotation of the cam discs, are transmitted to the respective lace point rods. For this purpose a pair of levers 107 and 108 are pivotally mounted on the front narrowing rod 70, these levers having toes 109 and 110 arranged to press against collars 111 and 112 respectively provided on the point rods 39 and 40 and being continuously held in such bearing relation by coiled springs 113 and 114 suitably anchored to a stationary portion of the machine frame.

Each of the depressions 96 in the edges of the cams 77 and 78 may be arranged to correspond to one or more needle spaces in the knitting field 20 of the machine, according to the pattern to be worked in the knitted article and the two pattern cams 77 and 78 are preferably enabled to position the lace points 31 and 32 in any desired spaced relation up to a total of approximately 25 sixty needle spaces, in any desired location across the knitting field of the machine.

The dipping operation of the lever 52 will in each instance effect a simultaneous advance of the cams 77 and 78 a distance equal to one of the depressions 96; and as the cams are faced in opposing relation the cam 78 will be moved clockwise in the direction of its increasing radius and the cam 77 also clockwise in the direction of its decreasing radius. The levers 98 and 99 will thus 35 be actuated by the cams 77 and 78 and will in turn engage the collars 105 and 106, which are constantly pressed against the toes 103 and 104 by means of the springs 113 and 114.

In the form illustrated in the drawings the 40 lever 99 will effect movement of the lace point 32 to the left while the lever 98 will effect movement of the point 31 to the right, so that the points will be caused to approach each other to the extent determined by the configuration of the depressions 96 and the number of dips of the lever 52, which latter movement is prescribed by the buttons 67 on the pattern chain 66. When the cams have traversed to the limit of their rotative movement the follower 102 of lever 99 will 50 have reached the outer portion 94 of cam 78, and the follower 101 of lever 98 will be located in the dwell 97. At this point the cam piece 85 operatively positioned in the raceway 75a of the ratchet wheel 75, coacts with the arm 83a of pawl 55. 83 to raise the latter out of engagement with 75; whereupon, the operation of the cams 77 and 78 and, in turn, the point bars 39 and 40 is discontinued. The handle 83b is provided for manually lifting the pawl 83 out of engagement with 60 the ratchet wheel 75. The cams are then returned to their initial positions, shown in Fig. 6, by means of a hand wheel 115, provided as a means for manually setting the cam discs to the desired starting or other position, during such 65 return of the lever-followers the lace points will be moved away from each other, in position to recommence the prescribed cycle of operative movement toward each other.

The hand wheel 115 is loosely mounted on a 70 collar 116 provided on a screw threaded extension 117 of the shaft 74, and is normally held outwardly against a stop head 118 at the end of the collar 116 by means of a spring 119. The hand wheel is provided with an inwardly extending 75

finger 120 the free end of which is disposed substantially opposite, and adjacent to the teeth of the ratchet wheel 15 whereupon, by moving the hand wheel inwardly against the action of the 5 spring 119 the said free end of the finger engages one of the teeth of the ratchet wheel and locks the said hand wheel to the ratchet wheel, whereupon rotation of the hand wheel in one direction or the other will correspondingly rotate the 10 ratchet wheel and the cam discs 17 and 18 operatively connected therewith. Upon releasing the hand wheel the spring will return the same to its outer inoperative position, releasing the finger 120 from the ratchet wheel to permit normal 15 operation of the latter.

The depressions 96 in the cam edges may be arranged in any desired way, so as to represent the pattern to be worked out in the knitted material. That is to say, a single depression may 20 represent any desired number of needle spaces; and the elevations may likewise be of any desired height or duration. Also, the elevations and depressions in the two cams may be arranged so that the lace points may be caused to move 25 back and forth any number of times while dipping in a single course.

During the step by step movement of the lace points toward each other any desired number 30 of dips may be made to pick up loops from certain of the needles 29 and transfer the same to other needles for the production of any predetermined complementary lace clock effect, as prescribed by the usual pattern chain controlled mechanism of the knitting machine.

35 The dipping motion for picking and transferring the stitch loops, in the present instance, is substantially the same as that used in well known conventional types of flat knitting machines of the type noted, and further detailed explanation 40 of the construction and operation thereof is therefore deemed unnecessary in the present case.

Figs. 10, 11 and 12 of the drawings illustrate an application of the invention to a conventional full fashioned knitting machine provided with 45 lace clock mechanism L for controlling movements of the lace points two of which, designated 123 and 124 respectively, are provided in each knitting section of the machine. The machine embodies the usual narrowing lift mechanism including narrowing lift levers 57a, cam followers 58a and cams 59a, and also the conventional needle actuating mechanisms comprising needle cam and lever members 220—222 and presser cam and lever members 223—225.

55 The lace points 123 and 124 are carried by 60 holders or fingers 125 and 126 rigidly secured to lace rods 127 and 128 respectively, mounted for movement longitudinally of the machine in guide arms 129 secured to the front narrowing shaft 135, which latter also carries a lock stitch or picot shaft 130. The machine also includes, for each 65 knitting section, a conventional needle bar 132, narrowing points 133 and narrowing mechanism N for operating the latter, such narrowing mechanism including the front narrowing shaft 135 secured to the guide arm 136 carried on the back narrowing shaft 137, and the narrowing rods 138 mounted in the brackets 139 secured to the front narrowing shaft 135.

70 The lace point rods 127 and 128 are provided, intermediate their ends, with opposing rack portions 140 and 141, joined together by a small pinion 142 fixed in a housing 143 mounted on the front narrowing shaft 135. A collar 144 is 75 arranged on the lace point rod 127 for coopera-

tion with a tension lever 146 mounted on the narrowing shaft 135, to normally urge the point rods together. The lever 146 is provided with a spring 148 for this purpose, one end of the spring being secured to the lever and the opposite end to a fixed portion of the frame of the machine. The action of the levers is thus smooth, positive and uniform at all times. The lock stitch or picot bar 131 is provided with a lever 147 and spring 149 for a similar purpose. 10

Any of the various known types of lace point rod actuating mechanisms suitable for the purpose may be employed to actuate the rod 128; preferably, and as shown, the Reading lace clock attachment is employed for this purpose, this 15 attachment and its operation in connection with the Reading full fashioned knitting machine being well-known in the art and described in a brochure entitled "Reading Lace Clock Attachments" (copyright 1931), published by the Textile 20 Machine Works, Reading, Pennsylvania.

In the present instance the lace clock mechanism L is employed to shift the lace point rods and hence the lace points to different predetermined positions. Such mechanism here includes 25 a sliding stop member 150 arranged to cooperate with a guide bracket 151 through the medium of which the lace point rod 128 is shifted to the right, the end of the latter rod being engaged as seen at 152. This causes the rack 141 to move 30 through the housing 143 and imparts rotational movement to the pinion 142. The pinion, being fixed, therefore, pulls the lace rod 127 to the left, thus imparting opposed motion to the lace rods. 35

Consequently, if the point finger 126 on the left end of the knitting head is moved to the right the finger 125 on the right will be moved to the left, thus resulting in the production of complementary symmetrical design portions in 40 the knitted fabric as described in connection with the form of the invention shown in Figs. 2 to 9. In the present instance the extent of the shifting movement imparted to the lace rods is determined in the following manner. 45

The design to be reproduced in the knitted article is prescribed by a pattern chain 153 having, in this instance three rows of screws 154, applying to loop selection of ten different heights, fastened to the chain 153 and arranged to be 50 successively brought to position under the adjustable end of one of three stepped segment levers 155. Each lever is provided with ten steps, the steps being advanced successively to cover a distance of three needles. The two points thus 55 afford a working spread of sixty needles, imparting a wide range to the design possibilities of the invention.

The lace point rods 127 and 128 are normally held in the position shown in Fig. 10 by means 60 of a vertical slide member 156 having a cam face arranged to engage a follower 157 provided on the guide bracket 151, which latter is rigidly connected to the sliding stop 150. At the same time the segment levers 155 are held up by a 65 fork 159 connected to the vertical slide 156, so that the proper pattern screw may be moved under the requisite segment. When the latter occurs the sliding stop 150 will rest against the 70 step of the segment which corresponds to the predetermined alignment of the lace points and stitch loops; and the end of the lace point rod 128 will be moved against the guide bracket 151 in the position assumed by the latter incident to such engagement of the sliding stop and seg- 75

ment step. The conjoint movement of the lace point rods will thus properly position the lace points for picking up and transferring selected loops.

- 5 The selected segment lever 155 will be held stationary until the narrowing machine has dropped down, caused the lace points to pick up their loops, and cleared the tips of the needles. At this point the eccentric stud 160 on which 10 the three segments 155 are mounted will be oscillated through the action of a cam linkage 158, and the segment will be forced a one-needle distance to the right, carrying with it the guide 151 and point rod 128, and moving the point rod 127 15 to the left. The points then place the lifted loops over the needles adjacent to those from which they were removed. The segment is again held stationary until the loops have been replaced on the respective needles and the narrowing machine again lifted. After this has occurred the 20 pattern screw is moved from contact with the segment, the segments and vertical slide are returned to their initial highest positions, and the machine will then be ready to position the points 25 for another lace operation.

Provision is made to effect left or right movement of the segments 155, during loop shifting, through means of the cams 122 and 134 and their respective followers 122a and 134a which, in turn, 30 operate the cam linkage 158. Clockwise oscillation of the eccentric stud 160, effected during the operation of cam 122, shifts the segments a one-needle distance to the left; whereas, a counter-clockwise oscillatory action of 160, produced by 35 the cam 134 shifts the segments a corresponding distance to the right. The presence of a screw in the loop shifting row of the pattern chain 153 controls leftward loop shifting of the segments 155; whereas the absence of a screw causes 40 a right shifting thereof.

A lace course regulator R is provided as part of the lace clock attachment L, as a means for automatically counting the number of plain courses to be knitted between any two lace courses, 45 depending upon the height of the control screw on the course regulator section of the pattern chain 163. The motion of the course regulator segment, which is acted upon by the pattern chain, is transmitted through levers 161 and 162 to a stepped counter plate or segment 163 which 50 works between the end of a bell crank lever 164, operated by the cam shaft 165, and a slide member 166. Toward the end of the lace making cycle this bell crank 164 is forced to the right 55 by the action of a cam on the cam shaft, this motion in turn being transmitted to the counter plate 163. A part of the counter plate motion is then communicated to the slide member 166, the amount of movement depending upon which 60 step of the counter plate is in position to function.

A rod 167, rigidly connected to slide member 166, carries hook 173; thus when 167 is in its extreme left position 173 lifts the regular chain motion lock lever 168 which releases the usual cam shaft shifting mechanism. A ratchet 169 is connected to the slide member 166 by means of a rack and pinion 170, this ratchet 169 being moved one tooth to the left during each knitting cycle by means of a cam lever 171 acting on a pawl 172.

Provision is made to effect dipping of the narrowing machine for operation of the lace clocking attachment without activating the narrowing head N, Fig. 10, through means of the roller

shifting device mechanism, shown in Fig. 11, which is substantially the same as that previously explained in conjunction with the mechanism illustrated in Fig. 3. However, in this case the cam follower 206 is positioned adjacent the 5 narrowing head actuating cam 207 and will in turn, normally become aligned therewith whenever the cam shaft 165 is rightwardly shifted; thus, the cam follower must be shifted along with 10 165 whenever the latter is axially repositioned to produce lace work. Thus when the buttons 208 on the main pattern chain 209 lift the lock lever 168 the machine will be operated through the usual narrowing cycle; whereas, when said lock lever 168 is tripped by hook 173, 15 which forms a part of the lace clock attachment, a lace clocking operation will be effected.

Coincident with the tripping of the lock lever 168 by hook 173 fastened to and moving in conjunction with rod 167, member 211, in turn fastened to 20 167, through means of the affixed set screw 210 abuts latch 212 and allows a roller 213 to drop into operative engagement with a face cam 214 mounted on the cam shaft 165. The roller is carried on a swinging extension 215a 25 of a centrally pivoted lever 215 connected to a rod 216 which slidably controls, by means of a centrally pivoted lever 217, the position of the shiftable roller 206 relative to the cam 207. The roller 219 operates in the manner previously described to raise the roller 213 out of alignment with the face cam 214 following the operation thereof. The roller 206 is carried by a lift lever 218 which controls the operation of the narrowing head mechanism N in the usual well known manner. It will be observed in contrast to the mechanism of Fig. 3, that this device shifts the narrowing head cam follower 206 in the direction of cam shaft shifting during the formation of lace and remains inoperative during narrowing; the reverse action takes place in the aforesaid device illustrated in Fig. 3.

At the end of the lace forming cycle the slide member 166, rod 167 and ratchet 169 are moved to the right a distance corresponding to the 45 number of plain courses desired. Then, at each knitting revolution the ratchet 169, slide member 166 and rod 167 are progressively moved back toward the left until the lever 173 lifts the chain motion lock lever 168, which in turn allows 50 the cam shaft 165 to be shifted in the usual manner, thus bringing the lace clock mechanism L into operation. Lace clocking now continues in the same course until a link of the pattern chain 153 bearing a screw 154 to act on the course regulator segment comes into position under such segment, whereupon the lace clock mechanism will be removed from action until the number of courses have been completed corresponding to the height of the control button.

Figs. 13 and 14 of the drawings illustrate another embodiment of the invention; more particularly in relation to the means for conjointly actuating the lace point rods, here designated 174 and 175. In this instance the point rods 65 are supported and guided in operative position by a plurality of housing members 129 which also carry the lock stitch or picot shaft 177.

The housing member 176 as shown includes a back plate 178 which is suitably secured to 70 the front of a bracket 179 through which the narrowing rods 180 and 181 extend. A plurality of such brackets are suitably secured to the front narrowing shaft 182 as by bolts 183.

To move the lace point rods 174 and 175 in 75

unison, the housing member 176 is formed with a pair of spaced channels 184 and 185 parallel with and close to the bores through which the lace point rods extend; and a pair of rectangular 5 slide members 186 and 187 are freely movable within said channels. Each of the slide members is provided with a central rectangular open portion, designated 188 and 189, respectively, and a pair of bearing shoes 190 and 191, of substantially 10 the same width but of less height than the openings 188 and 189, are mounted within the latter. These shoes 190 and 191 are joined by a rocker 192 which has a central pivotal mounting in the body of the housing and is pivotally connected 15 at its opposite ends to the shoes 190 and 191 as seen at 193 and 194 respectively.

The sides of the housing are extended outwardly between the channel portions 184 and 185 as seen at 200 and 201, to a point substantially flush 20 with the outer surface of the rocker 192; and a cover plate 202 is secured to the body of the housing to enclose the rocker and other parts. The central part of this cover engages the outer ends 25 of the side extension portions 200 and 201 and includes a bearing 203 for the outer end of the rocker spindle 195 while the ends of the cover plate abut against the front wall of the housing body. A central chamber 204 is thus afforded for 30 movement of the rocker, while the housing portions 200 and 201 are arranged to function as stops to limit movement of the rocker in both directions. However, the inner edges 205 of the 35 portions 200 and 201 may be beveled to afford a full range of oscillatory movement to the rocker as determined by the travel of the shoes 190 and 191 in their respective angular openings.

The arrangement of the slides, shoes and rocker is such that as the slide 186 is moved to the left, for instance, the shoe 190 will move with the 40 slide and by reason of its connection with the rocker 192 will move downward in the angular opening 188 as it turns the rocker about its pivotal mounting at the spindle 195. At the same time the shoe 191 at the opposite end of the rocker will communicate the latter's oscillatory movement to the slide 187, and the slide 187 will be moved to the right as the shoe 191 moves upward in the angular opening 189. The opposite movement of the two slides will continue until the shoes reach the respective ends of the angular 50 openings; and thereafter a reversal of movement imparted to either of the slides will result in communication of opposed movement to the other slide in like manner.

The movement of the slides 186 and 187 as just 55 described is communicated to the lace point rods 174 and 175 by means of collars 196 and 197 secured to the rod 174 in abutting overlapping relation with opposite ends of the slide 186, and similar collars 198 and 199 secured upon the rod 60 175 in like relation to the slide 187. Thus as one lace point rod is moved in one direction, its movement will be translated into an opposite directional movement of the other point rod.

The lace point rods 174 and 175 may be operated 65 by lace clock mechanism in a manner similar to the lace point rods 127 and 128 shown in Fig. 10, or in any other suitable way.

The collars 105 and 106 may be adjustably 70 mounted on the lace point rods so as to cooperate with different sized cams 77 and 78 and the cams 77 and 78 may also be of different individual shapes or patterns for production of different cycles of movement for the lace point rods.

75 Any of the lace point holders may also be ad-

justably mounted on the lace point rods so that the points may be secured in any desired position; and any number of lace points may be used on the rods in each section of the machine.

The present invention makes possible the production of practically any curved or otherwise shaped design in complementary, symmetrical form. Also, designs covering a distance of sixty 10 needles can be produced at the center of the leg blank of a stocking to form an instep design when the stocking is seamed; and this results in the production of a distinctly new and effective decorated stocking.

Of course, the improvements specifically shown and described, by which I obtain the above results, can be changed and modified in various ways without departing from the scope of the invention herein disclosed and hereinafter claimed.

What I claim is:

1. A full-fashioned stocking knitting machine 20 comprising points each for forming a lace clock like the clock formed by another point, and means for simultaneously actuating the points each to form successive lace openings on the center of its clock in a stocking blank being 25 knitted and to form lace openings at either side of the center of the clock in figures reverse to the corresponding figures at the opposite sides of the center of another clock, said means including carrier rods for the points, a motion-reversing device between the rods including a rack on each rod and a gear cooperating with the racks between the rods for actuating the rods simultaneously in opposite directions, and pattern means for controlling the said actuation of 30 the rods.

2. A full-fashioned stocking knitting machine 40 comprising points each for forming a lace clock like the clock formed by another point, and means for simultaneously actuating the points 45 each to form successive lace openings on the center of its clock in a stocking blank being knitted and to form lace openings at either side of the center of the clock in figures reverse to the corresponding figures at the opposite sides 50 of the center of another clock, said means including carrier rods for the points, a motion-reversing device between the rods including a rocker lever pivotally mounted between its ends and cooperating adjacent to its ends with the 55 respective carrier rods for actuating the rods simultaneously in opposite directions, and pattern means for controlling the said actuation of the rods.

3. A full-fashioned stocking knitting machine 55 comprising points each for forming a lace clock like the clock formed by another point, and means for simultaneously actuating the points 60 each to form successive lace openings on the center of its clock in a stocking blank being knitted and to form lace openings at either side of the center of the clock in figures reverse to the corresponding figures at the opposite sides of the center of another clock, said means including carrier rods for the points, a motion-reversing device between the rods including duplicate cams reversely actuatable about a common axis, and means including followers disposed one 65 between each cam and one of the carrier rods 70 other than the carrier rod for actuation by the other follower for actuating the rods simultaneously in opposite directions.
